RECLINING CHAIR

Peter T. Grabill, Houston, Tex.

Application April 17, 1951, Serial No. 221,443

3 Claims. (Cl. 155—106)

1

This invention relates to an article of furniture, and more particularly to a chair.

The object of the invention is to provide a chair which is constructed so that it will support a person in a sitting position or a reclining position.

Another object of the invention is to provide a chair which is ruggedly constructed, comfortable to use, and wherein the chair of the present invention will occupy a minimum amount of space, the chair being readily moved so that a person can be supported in a sitting or reclining position.

A further object of the invention is to provide a chair which is extremely simple and inexpensive to manufacture.

Other objects and advantages will be apparent during the course of the following description.

In the accompanying drawings forming a part of this application, and in which like numerals are used to designate like parts:

Figure 1 is a side elevational view of the chair constructed according to the present invention;

Figure 2 is a top plan view of the chair of the present invention, with the cross pieces removed;

Figure 3 is an end elevational view of the chair of the present invention;

Figure 4 is a sectional view taken on the line 4—4 of Figure 1;

Figure 5 is a sectional view taken on the line 5—5 of Figure 1.

Referring in detail to the drawings, there is shown a chair which includes a stand, as indicated by the numeral 10. The stand 10 comprises a pair of spaced parallel, horizontally disposed bases 11 for engagement with the floor or ground, and extending upwardly from each of the bases 11 is a leg 12, the legs 12 being secured to the bases 11 by suitable securing elements, such as screws or nails 14, Figure 1. Secured to the upper end of each of the pair of legs 12 is a bracket 15, the brackets 15 being secured to the legs 12 in any suitable manner, as for example, by glue or cement.

The chair of the present invention further includes a frame which comprises lower arms 16. It will be seen that the arms 16 are arranged in pairs, and one pair of arms 16 is provided for each of the legs 12, the arms 16 being spaced apart and slidably receiving therebetween the legs 12.

Arranged in spaced relation above each set of lower arms 16 is a pair of spaced upper arms 17. It will be seen from Figures 2, 4 and 5 that the arms 17 are arranged in pairs, there being a space between each of the arms 17 in a pair for receiv-

2

ing therebetween the upper ends of the legs 12. Extending across the upper edges of each pair of upper arms 17 and secured thereto is a cross piece 18.

Extending upwardly from the rear ends of the lower arms 16 and upper arms 17 is a pair of spaced parallel bars 19. The bars 19 are interposed between the rear ends of the arms 17 and 16, the bars 19 being pivotally connected to the arms 17 by means of a pin 20. The lower ends of the bars 19 are pivotally connected to arms 16 by means of a pin 21. Extending between the upper ends of the bars 19 and secured thereto in any suitable manner is a tie rod 22. A flexible support member 23 has one end secured to the tie rod 22, and the flexible support member 23 may be fabricated of any suitable material, such as canvas. A body member 24 extends between the pairs of lower arms 16 and is secured thereto, and the other end of the flexible support member 23 is secured to the body member 24. Thus, the support member 23 provides a comfortable support for the occupant of the chair.

The bracket 15 extends into the space between the upper arms 17 and the bracket 15 is pivotally connected to the upper arms 17 by means of a pin 25.

Depending from the front end of the frame is a leg support 26. The leg support 26 includes a pair of spaced parallel levers 27, and extending between the pair of levers 27 and secured thereto is a pair of spaced parallel cross members 28 and 29. A brace 30 extends between the pair of legs 12 and is secured thereto for strengthening the frame 10. The upper ends of the levers 27 project into the space between the arms 17, and the levers 27 are pivotally connected to the arms 17 by means of pins 31, the levers 27 being pivotally connected to the lower arms 16 by means of pins 32. The chair further includes a pair of chains 33. Each of the chains 33 has one end connected to one of the legs 12, while its other end is connected to the upper arms 17, the chains 33 serving to limit movement of the parts of the chair.

In use, the parts of the chair may be arranged as shown in Figure 1, so that a person can comfortably be supported in an upright position. Then, if the person desires to lean back or be supported in a reclining position, the person can engage the leg support 26 with his feet, or exert a backward pressure against that portion of the fabric 23 which is arranged between the bars 19. This will cause the chair parts to present a relatively flat surface so that the person can be supported in a reclining position.

The chair of the present invention is con-

structed so that a person can sit in the chair in an upright position or in a reclining position, the chair being ruggedly constructed and wherein a person will be comfortably supported. Also, the chair will occupy a minimum amount of space and will be inexpensive to manufacture. The supporting portion of the chair hangs or swings on the stand 10. The brace 30 serves to stabilize the stand and the brackets 15 permit the chair to be moved into and out of a position for supporting the occupant in a reclining position. The top arms 17 support the entire weight, thereby leaving the lower arms 16 free to move back and forth. The cross pieces 18 provide a cover or shield whereby the person's arms will be conveniently supported by these members. The fabric support member 23 will be able to move in arc or will have a rocker-like movement. Further, it will be seen that the upper and lower arms are not parallel to each other, so that the chair will not become locked when the person is being supported in a reclining position. Thus, the chair can move from a sitting position to a reclining position or vice versa without any chair adjustment being required.

What is claimed is:

1. In a chair, a stand comprising a pair of spaced parallel horizontally disposed bases, a leg extending upwardly from each of said bases and secured thereto, a horizontally disposed brace extending between said legs, a frame comprising a pair of spaced parallel lower arms arranged in spaced relation with respect to each of said legs, a pair of spaced upper arms arranged above each pair of lower arms and receiving therebetween the upper ends of said legs, a bracket secured to each of said legs and pivotally connected to said upper arm, a cross piece at each side of said frame, each pair of said upper arms having secured upon its upper edges a cross piece, a pair of spaced parallel bars, each of said parallel bars being pivotally connected to a pair of lower arms and at a spaced point to a pair of upper arms, said parallel bars extending above the pairs of upper arms, a horizontally disposed tie rod extending between the upper ends of said bars and secured thereto, a body member extending between the lower pair of arms and secured thereto, a flexible support member extending between said tie rod and body member and having its ends secured thereto, and a leg support, said leg support at each side being pivotally connected at spaced points to a pair of upper arms and to a pair of lower arms.

2. In a chair, a stand comprising a pair of spaced parallel horizontally disposed bases, a leg extending upwardly from each of said bases and secured thereto, a horizontally disposed brace extending between said legs, a frame comprising a pair of spaced parallel lower arms arranged in spaced relation with respect to each of said legs, a pair of spaced upper arms arranged above each pair of lower arms and receiving therebetween the upper ends of said legs, a bracket secured to

each of said legs and pivotally connected to said upper arms, a cross piece at each side of said frame, each pair of said upper arms having secured upon its upper edges a cross piece, a pair of spaced parallel bars, each of said parallel bars being pivotally connected to a pair of lower arms and at a spaced point to a pair of upper arms, said parallel bars extending above the pairs of upper arms, a horizontally disposed tie rod extending between the upper ends of said bars and secured thereto, a body member extending between the lower pair of arms and secured thereto, a flexible support member extending between said tie rod and body member and having its ends secured thereto, a leg support, said leg support at each side being pivotally connected at spaced points to a pair of upper arms and to a pair of lower arms, a leg support, said leg support comprising a pair of spaced parallel levers pivotally connected to said arms, and spaced parallel cross members extending between said levers and secured thereto.

3. In a chair, a stand comprising a pair of bases, a leg extending upwardly from each of said bases and secured thereto, a brace extending between said legs, a frame comprising a pair of lower arms arranged in spaced relation with respect to each of said legs, a pair of spaced upper arms arranged above each pair of lower arms and receiving therebetween the upper ends of said legs, a bracket secured to each of said legs and pivotally connected to said upper arms, a cross piece at each side of said frame, each pair of said upper arms having secured upon its upper edges a cross piece, a pair of spaced parallel bars, each of said parallel bars being pivotally connected to a pair of lower arms and at a spaced point to a pair of upper arms, said parallel bars extending above the pairs of upper arms, a tie rod extending between said bars and secured thereto, a body member extending between the lower pairs of arms and secured thereto, a support member extending between said tie rod and body member and having its ends secured thereto, and a leg support, said leg support at each side being pivotally connected at spaced points to a pair of upper arms and to a pair of lower arms.
